UNITED STATES PATENT OFFICE.

WALTER F. ROLSTON, OF ROCKFORD, ILLINOIS, ASSIGNOR TO BURSON MANUFACTURING COMPANY, OF ROCKFORD, ILLINOIS, A CORPORATION OF ILLINOIS.

KNITTING-MACHINE.

1,072,365.

Specification of Letters Patent.

Patented Sept. 2, 1913.

Application filed June 11, 1912. Serial No. 702,978.

To all whom it may concern:

Be it known that I, WALTER F. ROLSTON, a citizen of the United States, residing at Rockford, in the county of Winnebago and the State of Illinois, have invented certain new and useful Improvements in Knitting-Machines, of which the following is a specification.

Heretofore in the yarn feeding apparatus of knitting machines, the constant feeding of yarn through the feed stops caused small particles of lint to accumulate and finally caused the stops to become inoperative altogether, thus causing the operators of the machines to be on a constant lookout to see that the stops are kept clean and in perfect working order.

In my invention I have a feed stop, that by its own action keeps the holding surfaces free from the accumulation of small particles of yarn, thus making it automatic and requiring no attention as to its operativeness.

In the accompanying drawings, Figure 1 is a side elevation of the yarn feeding apparatus of a knitting machine. Fig. 2 is an enlarged front view of a yarn feed stop, a portion being broken away to show the yarn held thereby. Fig. 3 is an enlarged plan of the yarn stop, showing the method of its support. Fig. 4 is an enlarged plan section on the line *a—a* of Fig. 2. Fig. 5 is a front elevation of the yarn feeding apparatus.

In the drawings only so much of a knitting machine is shown as is necessary to explain and describe my invention. The machine has a bed 1, a horizontal reciprocating yarn carrier 2, and a yarn changer 3 which are well known factors in knitting machines.

Suitably supported by the bed of the machine is the vertical rod or post 4, which furnishes the main support for the feeding apparatus. Clamped to the post 4 is a bracket 5, which has formed at its extremity two oblique jaws 6 and 7, riveted together carrying a plurality of horizontal tension wires 8, which are held parallel by the auxiliary jaws 6½ and 7½ also riveted together, and rigidly secured to the bracket 5 is a lower tension wire 8½, parallel to the wires 8, but lying in a different plane as is clearly shown.

The adjustable sleeve bracket 9 is clamped to the post 4, above the bracket 5, and carries 55 in its sleeve a horizontal rod 10, which lies

parallel to the tension wires 8. Mounted on the rod 10 and carried rigidly by a set screw, is the collar 11, having the extending support 12, by which at its upper extremity is rigidly carried the bolt 13, upon which is 60 pivotally mounted the arm 14, having connection with one end of a spiral spring coiled about the bolt 13, the other end of the spring being fastened to the bolt 13, the tension of the spring forcing the arm in a contra-clockwise direction, said arm carrying a wire spring 15, one end of which is held in the arm 14, the other end having an eye or loop. The bolt 17 is fastened rigidly, intermediate the bolt 13 and the rod 10, to 70 the support 12, and carries a spring tension wire 18, one end of which is coiled about the bolt 17 in a clockwise direction and fastened thereto, and the other end carrying an eye or loop for the passage of yarn. A stop 19, 75 riveted to the support 12, limits the downward movement of the tension wire 18.

The collar 20, fastened rigidly to the rod 10 by a set screw, carries a vertical rod 21, which is bent just below the collar 20 to 80 a horizontal position, and supports at its extremity a smaller rod 22, which lies horizontal and parallel to the rod 10. Supported also by the collar 20, but on the side opposite to the support of the rod 21, is the 85 rod 23, which lies at an angle parallel to the jaws 6 and 7, and carries a plurality of eyes 24, spaced intermediate the tension wires 8.

Rigidly secured to the rod 22 is the yarn feed stop, the object of my invention. A 90 wire support 25 rigidly secured longitudinally to the rod 22, has one end 25½ that is downstanding, and bends forward horizontally supporting the lower portion of the stop 26; the other end of the wire support 95 25 extending over the rod 22 and at right angles to it, forming a rigid support at the top of the yarn stop, as at 27. At one end of the base bar 28 are rigidly secured the two members 29 and 30, to each side of the 100 bar and directly opposite each other, their inner edges slightly beveled as at 31, and having their tops brought together, a small block 32 of suitable thickness placed between them and the three riveted together. The 105 opposite end of the base bar 28 is slotted as at 33, and has pivoted therein a holding bar 34 which is adapted to rest intermediate the members 29 and 30, having clearance on each side so that yarn in being held will not be 110

pinched too tightly, as is shown clearly in Fig. 4; the downward movement of the bar 34 being limited by the shoulder of the slot 33 and its upper movement by the block 32.

The passage of the yarn through the feeding apparatus is as follows: The yarn 35 comes from the spool or bobbin, passes over the wire 8 $\frac{1}{2}$, then alternately over the wires 8 and through eyes 24, as shown, thus forming a tension for the yarn; from here the 5 yarn passes through the eye supported by the spring tension wire 18, then passes through the feed stop, up through the eye formed by the spring tension wire 16, and 10 then down to the yarn carrier 2 which feeds the yarn to the needles. The action of my improved yarn feed stop will be readily seen by a description of the action of the feeding apparatus. In the drawings the 15 yarn carrier 2 holding the yarn 36, is shown just about to start its reciprocation. The yarn carrier is carried across the needles, thus drawing the spring tension wire 16 to a position as shown by the dotted lines 20 16 $\frac{1}{2}$ in Fig. 1, and releasing the yarn from the yarn stop. Because of the design in the 25 shape of stockings, more yarn is required at some reciprocations than at others, a portion of the yarn is unused, which slack is 30 taken up by the spring tension wire 16. When the yarn carrier returns, and more 35 yarn is drawn in, the spring tension wire 16 will again assume the position 16 $\frac{1}{2}$ with the yarn 37 $\frac{1}{2}$ free of the stop, allowing additional yarn to be drawn through the eye carried by the spring tension wire 18, eyes 24, and tension wires 8 and 8 $\frac{1}{2}$. As additional yarn is thus being drawn, the spring 40 tension wire 16 will rise by the strength of the springs 15 and 16, and the spiral spring fastened to the arm 14, thus pulling the 45 yarn 37 above the yarn stop, and the yarn feed will be stopped.

The operation of the feed stop is as follows: The upward movement of yarn 37 $\frac{1}{2}$ causes it to strike the bar 34 and follow its curvature, thus raising the bar to its most upward position, when the yarn will embrace the bar 34, as shown clearly in Fig. 4, 50 and by the binding contact of the yarn located between the bar 34 and the beveled edges of the members 29 and 30, the yarn will be held, thereby stopping the feed of the yarn from the bobbin through the eye 55 of the tension wire 18. When yarn is drawn by the yarn carrier 2, the spring tension wire 16 is again pulled down to position 16 $\frac{1}{2}$, and the yarn 37 $\frac{1}{2}$ is again drawn from the bobbin, the bar 34 will fall by its own 60 weight until resting on the shoulder of the slot 33. Heretofore with the bar 34 stationary, small particles of lint would accumulate along the surfaces 31, completely fill up the yarn passage, and allow the yarn 65 to feed continuously, whereby the function

of the spring tension wire 16 would be entirely destroyed, the yarn would soon tangle, break, and the feed of the yarn to the needles would be broken.

It can be readily seen that when small 70 particles of lint cling to either the bar 34 or members 29 and 30, the downward movement of the bar 34 would wipe them away, thus always keeping the stopping surfaces clean and effective.

While in the above description I have described the feeding of the yarn 35, it will be understood that a plurality of feeding apparatus can be carried on the rod 10, and I have shown a second such apparatus carrying the yarn 35 $\frac{1}{2}$ whose portion 36 $\frac{1}{2}$ leads 80 to the yarn changer 3. When the design of the knitting requires a different yarn, the yarn 36 $\frac{1}{2}$ will be automatically substituted for the yarn 36, the yarn 36 being then 85 held in the yarn changer 3.

I claim as my invention:

1. A yarn feed stop comprising a base bar formed with a slot, stationary members, 90 a bar pivoted in said slot, one end of said slot limiting the downward movement of the pivotal bar, and a stop lying intermediate the stationary members and limiting the upward movement of the pivotal bar.

2. A yarn feed stop comprising side members and a pivotal member, said members being disposed V-shape, the side and pivotal members each constituting a leg of the V and the pivotal member having its free end disposed intermediate said side members at the apex of the V, the pivotal member adapted to guide a thread being drawn taut along the portion of its edge lying intermediate its pivotal support and the joining of said edge with the side members, until said thread is gripped between the adjoining sides of said members, thereby stopping the passage of thread.

3. A yarn feed stop having two converging side members, a pivotal member having 110 its free end located intermediate said side members at substantially the narrowest convergent portion thereof, the pivotal member adapted to guide a thread being drawn taut along its edge in the direction of convergence of said side members and to be pivoted by such action, the thread thereby being gripped between the adjoining sides of said members thus stopping the feed of the yarn, and the pivotal member adapted, 115 when said thread is loosened, to be carried back from said pivotal position and to remove lint accumulated on said adjoining faces.

4. A yarn feed stop comprising a base bar, stationary side members and a pivotal member attached to the bar and spaced apart thereon from said side members, the stationary members and pivotal member converging from said bar, the convergent 125 130

- portion thereof being to one side of the pivotal attachment of said pivoted member, the pivotal member lying intermediate the stationary side members at the convergent portion and adapted when a thread is drawn through said convergent portion, to bind the thread against the sides of said stationary members thereby stopping the passage of yarn.
- 5 10 5. A yarn feed stop comprising stationary side members, and a pivotal member having its free end adapted to lie intermediate the side members and adapted when in its raised position to stop the passage of thread passing between the sides of the sta-
- 15

tionary members, said pivotal member being pivoted at one side of said thread passage through the members, and adapted upon releasing the tautness of said thread to fall to its normal position, this action causing the 20 side members to remove from said pivotal member any lint accumulated thereon by the stopping of the thread.

In testimony whereof I have hereunto set my hand in presence of two subscribing witnesses.

WALTER F. ROLSTON.
